PHOSPHORIZING NOZZLE

James R. Wyatt, Havertown, Pa., assignor to The Ajax Metal Company, Philadelphia, Pa., a corporation of Pennsylvania

Original application May 16, 1947, Serial No. 748,637. Divided and this application March 7, 1949, Serial No. 80,083

1 Claim. (Cl. 299—141)

1

My invention relates to apparatus for phosphorizing and especially for making phosphor copper.

A purpose of my invention is to reduce the accident rate and reduce or eliminate the health hazard in phosphorizing.

A further purpose is to eliminate the smoke nuisance incident to present methods of phosphorizing.

A further purpose is to increase the yield and also increase the rate of phosphorus absorption by molten metal at high yield and permit continuous operation.

A further purpose is to avoid the necessity of copper coating phosphorus before phosphorizing.

A further purpose is to avoid the difficulty and inconvenience due to the formation of red phosphorus.

A further purpose is to more accurately control the ultimate phosphorus content of the phosphor copper and more accurately regulate the rate of phosphorizing.

A further purpose is to melt white phosphorus remote from its point of dispensing, so that possible leakage incident to charging phosphorus to be melted will not create a hazard at the point of dispensing.

A further purpose is to pump from a melting pool to a dispensing pool of molten phosphorus by pressure on an inert liquid floating on the phosphorus of the melting pool and to dispense by pressure on an inert liquid floating on the dispensing pool, and desirably by introducing a measured quantity of inert liquid into a confined space containing the dispensing pool.

A further purpose is to maintain molten phosphorus under temperature control which will prevent formation of red phosphorus from the time it leaves a dispensing pool until it reaches the high temperature zone of the molten metal.

A further purpose is to obtain the measured quantity of inert liquid for dispensing from an inert liquid column above the dispensing pool.

A further purpose is to phosphorize molten metal by jets of phosphorus vapor proceeding laterally from a phosphorizing nozzle, preferably of carbon.

Further purposes appear in the specification and in the claim.

I have chosen to illustrate my invention by showing a few only of the many possible embodiments, choosing the forms shown from the standpoints of convenience in illustration, satisfactory operation, and clear demonstration of the principles involved.

Figure 1 is a diagrammatic vertical section of one phosphorizing apparatus embodying the invention.

Figure 2 is a top plan view of Figure 1.

Figure 3 is a diagrammatic vertical section of

2

a preferred phosphorizing apparatus which embodies a modification of the form of Figures 1 and 2.

Figure 4 is an enlarged central vertical section through the preferred phosphorizing nozzle.

Figure 4a is a fragmentary view corresponding to Figure 4, showing a modification.

Figure 5 is a section on the line 5—5 of Figure 4.

Describing in illustration but not in limitation, and referring to the drawings:

The present application is a division of my copending application Serial No. 748,637, filed May 16, 1947, now Patent No. 2,634,027 for Phosphorizing Methods and Apparatus, which relates to the general apparatus for phosphorizing.

Phosphorizing of molten metal is practiced largely in producing master alloys which are employed in the metallurgical industry, the most widely known being phosphor copper, which is used as a deoxidizing agent, and in the manufacture of phosphorus-containing alloys such as Phosphor bronze.

Phosphorus is likely to be a very hazardous material to handle, particularly because it is inflammable, it is very toxic, particularly in vapor form, and the effects are cumulative in the human body.

The handling of phosphorus is complicated by the fact that it exists in allotropic modification. For example, white phosphorus is quite inflammable in air and melts at about 111° F. At from 440 to 480° F. white phosphorus is converted to red phosphorus, which is more inert and of higher melting point. The practice in making phosphor copper has been to coat white phosphorus with a protective layer of copper, and to charge the copper coated cakes of phosphorus into the molten copper, preferably below the surface of the bath.

This has been a very hazardous occupation, as it is essential that the operator must not breathe phosphorus vapor. Furthermore it has been time-consuming and expensive both from a labor standpoint because of the time involved, and from a furnace standpoint because of the delay in the furnace cycle. The loss in phosphorus has been very considerable, adding to the expense, and since much of the phosphorus loss creates phosphorus pentoxide smoke, the smoke nuisance has been serious.

Various efforts have been made to overcome these and related difficulties. Demler U. S. Patent No. 1,287,653 and Nicholson U. S. Patent No. 1,425,679 distill phosphorus from a retort and conduct the vapor to the point of phosphorizing. The present inventor has experimented with this technique and has designed an apparatus of this character. The problem, however, is not simple as in the case of ordinary materials which do not exhibit allotropic change. It has been found that

almost inevitably some part of the retort or connections will operate at a temperature favoring the formation of red phosphorus, and at such locations red phosphorus accumulates rapidly, clogging the apparatus and necessitating frequent shut-downs for cleaning. Since the apparatus is initially thoroughly filled with phosphorus vapor, and white phosphorus is retained in many parts of the equipment, cleaning is a very hazardous occupation, and it becomes a question whether it is not safer to use the well known practice of charging copper coated cakes of white phosphorus. Added to this is the certainty that any leakage of phosphorus vapor from the retort may have fatal consequences to workmen.

Burns U. S. Patent No. 2,164,228 applies molten phosphorus to metal by an apparatus which is essentially a dropping funnel suspended above the molten metal bath, in which phosphorus is melted below water, and from which it is dropped under valve control into a nozzle beneath the surface of the metal. This presents the difficulty of exposing the entire mechanism to the heat of the molten metal bath, and hazarding difficulty or danger through leakage, since the dropping funnel must be opened periodically to introduce cakes of white phosphorus.

In accordance with the present invention, the difficulties of the various prior art processes are overcome without appreciable increase in the cost of the operation.

It has been found that by the present invention, the loss in phosphorizing copper can be cut to 20% of the loss presently encountered in charging copper coated cakes of white phosphorus. At the same time the smoke nuisance is largely eliminated. Handling of the phosphorus by the individual worker can be entirely eliminated. The step of copper coating the phosphorus is rendered unnecessary. The process is made continuous, with very excellent control over both the total amount of phosphorus alloyed, and the rate of alloying. The speed of alloying can be increased beyond that at present practiced.

The hazard through accident or impairment of health is practically eliminated, both from handling of phosphorus and from phosphorus vapor. The dispensing tank can be tightly closed and need not be opened at any stage of the operation, so that the danger of leakage of phosphorus vapor is greatly reduced. Labor cost is cut down.

In accordance with the invention, the formation of red phosphorus does not occur, and hazardous and troublesome cleaning to remove accumulations of red phosphorus from the apparatus is not necessary. The molten phosphorus is kept under temperature control from the dispensing pool to the high temperature zone of the molten metal, thus maintaining a temperature which will prevent formation of red phosphorus.

Considering first the form of Figures 1 and 2, I provide a tank 20 conveniently open at the top, and made from any suitable material such as steel or stainless steel. The tank is filled to a convenient height with inert liquid 21, suitably water. As the purpose of the inert liquid is partially heat transfer, partially prevention of combustion of white phosphorus, and partially displacement of phosphorus, it will be evident that water is the preferred inert liquid, but that other suitable inert liquids may be used, as, for example, phosphoric acid or, where the fire hazard can be controlled, a mineral oil such as kerosene (kerosene is not recommended because of the fire

hazard). The tank 20 is heated by any suitable means, such as gas burner 22 having a gas connection 23, an air inlet 24 and a combustion gas flue 25 suitably passing up through the tank 20.

Within the tank 20, two pools of molten phosphorus 26 and 27 are located, each having upon its surface a pool of inert liquid 28 or 29, which will be desirably identical with the inert liquid 21. The pool of molten phosphorus 26 and of inert liquid 28 is contained within a tank 30, and the pool of molten phosphorus 27 and of inert liquid 29 is contained within the tank 31. Both tanks are suitably of steel or stainless steel, in heat transfer relation with the tank 20, and the pool of inert liquid 21 contained therein. The tanks 30 and 31 may suitably be supported on a frame 32 in the bottom of the tank 20.

Access to the interior of the tank 31 is not necessary in the process, and one of the advantages of the process is the fact that the head 33 of tank 31 can be permanently gasketed or welded on at 34 to prevent the possibility of leakage, and particularly to prevent the possibility of any escape of phosphorus vapor, if vapors should be carried back from the discharge nozzle.

On the other hand, the head 35 of tank 30 is removably bolted and gasketed at 36, so that it can be readily removed to introduce white phosphorus to be melted in the pool 26.

The melting tank 30 is connected through its head 35 to a source of inert liquid under pressure. This is conveniently a pump 37 driven by a motor 38 having inlet at 39 from the pool 21 and discharging at 40 through flexible connections controlled by valve 41, the discharge passing directly to the pool of inert liquid 28.

The head 35 of tank 30 is also conveniently provided with a safety valve 42.

To permit transfer of molten phosphorus from pool 26 to pool 27, a connection 43 extends to near the bottom of pool 26 in tank 20, through union 44 and valve 45 to pool 29 above pool 27 in tank 31.

Tank 31 is equipped with mechanism to introduce a measured quantity of inert liquid into pool 29. This is accomplished by pump 46 driven by motor 47 having inlet at 48 (desirably connected to the pool 21, but broken away to avoid complication in the drawing) and discharging through connection 49, relief valve 50, pressure gauge 51, flow meter 52 (rotating type) and flow meter 53 (variable orifice type), check valve 54, and valve 55 to the head 33 of tank 31. An overflow valve to permit discharge of inert liquid from pool 29 in tank 31 is provided at 56.

As a means of checking the level of molten phosphorus in tank 31, float 57 is provided in float column 58 extending to the bottom of the molten phosphorus, open at the bottom and closed at the sides, and having indicator stem 59 in cover glass 60, closed at the top. The combined weight of the float and indicator is chosen so that it is less than the weight of the phosphorus displaced by the parts submerged in phosphorus, but greater than the weight of the inert liquid displaced by the total submerged parts if they were in inert liquid. All of this of course presupposes the weight of the molten phosphorus and inert liquid at the particular temperature at which they are held. Thus the float will float on molten phosphorus but will sink in inert liquid, the inert liquid being lighter than the molten phosphorus, and the position of the float will always indicate the top of the pool 27.

From the dispensing pool 27, discharge is accomplished to a discharge nozzle 61 below the

level of the molten metal 62 in a suitable furnace 63 by a connection 64 extending to the bottom of the pool 21. It is important that the molten phosphorus should not solidify in the discharge connection and should not get hot enough to form red phosphorus there, and therefore the discharge connection is jacketed, preferably by inert liquid, suitably withdrawn from the bath 21, at the preferred temperature of about 180° F. This is accomplished by a pump 65 driven by motor 66 which has inlet connections 66 to the pool 21 and discharges at 67 to water jacket 68 surrounding one portion of the discharge connection, then flowing through connection 69 and through water jacket 70 surrounding a bend 71 in the flexible connection. Discharge is through a conduit 72 which returns to the pool 21. The inert liquid connections 67 and 72 are suitably made flexible, since the connection 64 for flow of molten phosphorus to the nozzle is made flexible by a universal type joint 73. Discharge of molten phosphorus to the nozzle 61 is controlled by discharge valve 14, which is conveniently located between the heating jackets 68 and 70.

In Figure 3 I illustrate a variation in respect both to the nozzle construction, as later explained, and as to the arrangement for measuring inert liquid to be introduced into the dispensing pool.

A water column 75 is provided suitably in the form of a closed tank preferably extending to a height substantially above the pools 28 and 29. The water column 75 is provided with a liquid level gauge 76, suitably of the sight glass type familiar in boilers. Inert liquid inlet is provided to the inert liquid column by a connection 77 from pump 31 controlled by valve 78 and conveniently entering near the closed top of the inert liquid column.

Discharge of inert liquid from a point conveniently located below the gauge on the inert liquid column is provided by a connection 79 controlled by valve 80 and having a flow meter 81.

In order to force the inert liquid from the inert liquid column into the pool 29, I provide a source of gas under pressure, suitably an air compressor 82 driven by motor 83 and discharging compressed air through connection 84 and valve 85 to the top of the inert liquid in the inert liquid column 75.

In Figures 1 and 2, the nozzle is of conical form as indicated at 61, and has a conical interior bore 87 extending from end to end vertically and communicating with connection 64. This nozzle is made of suitable refractory material, preferably graphite.

In Figures 3, 4 and 5 I illustrate a variant form of nozzle 61' which is suitably tubular in exterior dimension and contains an interior conical bore 87 enlarging from the inlet to the outlet. The nozzle 61' is most conveniently manufactured by boring out a graphite electric furnace electrode or other similar carbon refractory cylinder. The nozzle is mounted in a metallic nozzle holder 88 having a side opening for the connection 64, a closure cap 89, a distribution chamber 90 and a discharge orifice 91 immediately above the bore 87. The nozzle holder has a tubular socket 92 which receives the upper end of the nozzle 61', making vapor-tight seal by a steel bellows 93 between the end of the nozzle and the base of the socket and a packing 94 clamped against the side of the nozzle by a packing ring 95 suitably threaded on the nozzle holder. The nozzle is held in the holder and drawn up tight against the

packing 93 by bolts 96 acting between radial lugs 97 on the holder and a split ring 98 attached in a recess 99 on the nozzle.

At intervals around the circumference of the nozzle above the bottom opening 100 of the bore, jet openings 101 are provided extending radially and preferably downwardly at an angle, as best seen in Figure 4. It has been found in practice that phosphorus drops through the orifice 91, is expelled in jets through the jet openings 101, extending for considerable distances in the molten metal surrounding the orifice, and thus being very effectively absorbed. When the volume of vapor is too great to discharge through the jet openings 101, it is, of course, free to discharge through the end opening 100, but the penetration into the molten bath is likely to be less extensive and more dependence is placed upon diffusion and stirring of the bath to obtain uniformity of phosphorizing.

It has been found in practice with the jet of the type of Figures 3, 4 and 5 and a bath of adequate size to maintain the jet preferably a foot or more below the bath surface, that there is no serious danger of phosphorus vapor not being absorbed by the molten copper. As an additional protection, however, against this contingency it is desirable to maintain carbon on the bath at 102, and to maintain an adequate supply of air so that the conditions will be oxidizing above the carbon (charcoal), and any possible phosphorus vapor discharging would be oxidized to phosphorus pentoxide. This feature is precautionary, however, as the small amount of smoke and the high yield indicate that little phosphorus is lost.

As the nozzle is used, the holes 101 may enlarge and the jet effect be lost, the vapor passing upward along the outside surface of the nozzle, without adequate contact with the metal. In Figure 4' I illustrate an annular enlargement, ring or shell 105 around the nozzle above the openings 101, which assures deflection of any rising vapor outwardly, and adequate contact with the molten metal.

In making phosphor copper the operation is usually continued until about 14% has been combined, the percentage being somewhat critical as in the case of higher phosphorus contents the alloy may take fire.

In operation, the apparatus is set up as shown, the gas or other fuel burner being maintained so that the inert liquid (water) will preferably be at a temperature of about 160 to 180° F. in the pool 21.

With all valves closed, the head 35 is removed from tank 30, and solid white phosphorus to be melted is introduced into the tank 30 to join the pool 26. Where the white phosphorus is in the form of cakes, these may simply be dropped through the inert liquid of the pool 28 into the pool 26. It is preferred, however, to insert a drum of phosphorus bottom up with the head removed as shown at 103 in Figure 1, using chain grips 104, so that the drum may discharge by the phosphorus melting out of the drum after the tank is closed. The head 35 is then reapplied and suitably gasketed at 36 on the tank 30. While it is desirable to have this gasketing tight, no harm will be done if there is a slight leakage as it is impossible for phosphorus vapor from the nozzle to flow back into tank 30 during phosphorizing, since the valve 45 is kept closed at such times. The only harm done by leakage at the gasket 36 is that some pressure will be lost in pumping molten phosphorus into the dispensing pool.

If any mistake is made in charging by which pieces or fragments of phosphorus drop into the pool 21, no serious harm is done as the pool 21 provides protection from fire and the phosphorus will simply remain at the bottom of the tank 20, from which it may be removed.

In order to transfer phosphorus from pool 26 to pool 27, valve 45 in the connection 43 between the tanks 30 and 31 is opened, overflow valve 56 on tank 31 is opened, and with pump 37 operating, valve 41 is opened to apply inert liquid pressure to pool 28 on pool 26 in tank 30. This results in forcing molten phosphorus from melting pool 26 through connection 43 into tank 31, where it drops into and forms part of dispensing pool 27. The level of molten phosphorus in pool 27 is shown at all times by float 57 on indicator 59, the molten phosphorus of the pool communicating with the float through the open bottom of column 60. As soon as sufficient phosphorus has arrived in pool 27, valves 41, 45 and 56 are closed and pump 37 is turned off.

In order to phosphorize, using the form of Figures 1 and 2, the nozzle 61 is inserted well below the level of the molten metal in furnace 63, manipulating the nozzle by means of universal joint 73. Pump 64 is started so that the exposed portions of connection 64 are well heated by the warm inert liquid from pool 21. To begin phosphorizing, pump 46 is started and valve 55 is opened to permit inert liquid to enter pool 29, and discharge valve 74 is opened to permit phosphorus to be displaced from pool 21 and discharge through the nozzle. Valves 55 and 74 are adjusted to obtain the desired flow as shown by flow meters 52 and 53. The quantity of phosphorus discharged by the nozzle can be determined, since it is equal to the quantity of inert liquid passing through the flow meters 52 and 53. The change in level of the float 57 can be used as a check, and to be sure that the pool 21 is not completely depleted.

The phosphorus dropping through the bore of the nozzle is very rapidly vaporized in the nozzle and discharged as vapor into the molten metal. In most cases, molten phosphorus never actually reaches the surface of the molten metal, but if it does it is very rapidly vaporized and the vapor carried into the molten metal. Where a nozzle of the type of Figures 3, 4 and 5 is used, this vaporization results in jets discharging through the jet openings 101 into the molten metal.

In the form of Figure 3, the pool 26 is filled as above described. With all other valves closed, the air bleed 84' from the inert liquid column is opened. Pump 37 is started, and valve 78 opened to introduce inert liquid through connection 77 to a suitable level at the upper part of the gauge, if the inert liquid level be unduly low. Valves 78 and 84' are then closed. Pump 82 is started and valve 85 opened to apply air pressure to the top of the inert liquid column, tending to force the inert liquid out of the column. Valve 80 is opened to connect the bottom of the inert liquid column with the pool 29 above the phosphorus dispensing pool 27. The nozzle 61' is suitably immersed well below the level of the molten metal 62 as shown in Figure 3, and the dispensing valve 74 opened. Molten phosphorus from the pool 27 is now displaced through the connection 64 which is of course suitably heated by the heating jacket 68 supplied with

heated inert liquid through pump 65 as previously explained. The rate of dispensing of molten phosphorus can be gauged by the flow meter 81, and the total quantity of phosphorus discharge 5 can be gauged by the difference in level of inert liquid on the gauge 76, which will correspond with the volume of phosphorus dispensed. This method of gauging is preferred because it is more accurate than the flow meter method.

It will be evident that by the present invention it is possible to introduce phosphorus to a molten metal bath without handling of the material from the time it is first charged for melting, and even this can be done by handling a drum and without individual handling of cakes. It will further be evident that at the time that dispensing takes place, the connection to the melting pool through the valve 45 is closed, so that the danger through leakage of the melting tank is avoided. It will also be evident that during dispensing, the molten phosphorus in the dispensing pool is protected not only by the pool of inert liquid covering it, but also by the inert liquid being supplied from the pump or from the inert liquid column.

In view of my invention and disclosure variations and modifications to meet individual whim or particular need will doubtless become evident to others skilled in the art, to obtain all or part of the benefits of my invention without copying the apparatus shown, and I, therefore, claim all such insofar as they fall within the reasonable spirit and scope of my claim.

Having thus described my invention what I claim as new and desire to secure by Letters Patent is:

In a phosphorizing apparatus, a metering device dispensing molten phosphorus at a controlled rate, a nozzle head connected with the metering device and having a socket provided with an opening, a carbon refractory nozzle element having a longitudinal bore tapering from a smaller cross section near an inlet end to a larger cross section near an opposite outlet end, and having a ring of radial holes outwardly directed from the bore to the outside near the outlet end, the nozzle element fitting into the socket at the inlet end of the nozzle, a collar surrounding and engaged with the refractory of the nozzle element located at a position intermediate between the inlet and outlet ends and screws extending longitudinally at spaced points around the circumference and interconnecting the collar with the nozzle head.

JAMES R. WYATT.
